UNITED STATES PATENT OFFICE.

ANDREW B. MILLER, OF BALDWIN, WISCONSIN.

LAUNDRY-MACHINE.

1,359,721.

Specification of Letters Patent. Patented Nov. 23, 1920.

Application filed December 26, 1919. Serial No. 347,563.

To all whom it may concern:

Be it known that I, ANDREW B. MILLER, a citizen of the United States, residing at Baldwin, in the county of St. Croix and State of Wisconsin, have invented a new and useful Laundry-Machine, of which the following is a specification.

My invention relates to laundry machines, and the object is to provide an improved machine of the kind in which material may be cleansed and the cleansing fluid then forced therefrom without necessitating handling of the material either during or between the operations. The various improvements will fully appear from the specification and claims and in the accompanying drawing, in which—

Figure 1 is a top or plan view of the improved machine. Fig. 2 is a side elevation 20 of the machine with the tubs in section on the line 2—2 in Fig. 1. Fig. 3 is a rear elevation of the machine viewing it as from right to left in Fig. 2. Fig. 4 is a partly 25 sectional view of the central tubes and vertical shaft in the tub, on an enlarged scale.

Referring to the drawing by reference numerals, 5 designates any suitable form of base, preferably a portable base, upon which are provided legs 6 supporting an outer tub 7. This tub is water tight and provided 30 with a discharge valve (not shown because it is common on washing machines). Fixed at 8 to the bottom of said tub is a central sleeve 9, which extends so far upward into 35 the tub that the usual amount of cleansing fluid placed in the tub will never get above the top of it.

Rotatable about said sleeve is a second sleeve, 10, whose lower end is fixed at 11, 40 to the bottom of a perforated tub 12, which is smaller than the main tub 7. Fixed at the upper end of the sleeve 10 is a cone 13, which is threaded on a central vertical shaft 14. Fixed at the upper end of said screw- 45 shaft 14 is a hollow cone 15, and in a notch 16 in the top of the shaft is pivoted at 17 a lever 18, having an indenture 19 adapted to be engaged by a catch 20, which is constantly pressed upward by a spring 21.

50 The lower end of the shaft is journaled in a bearing 22 fixed on the base, and above said bearing are fixed on the shaft a small bevel gear 23 and a large bevel gear 24, which are operated alternately to rotate the 55 perforated tub at fast or slow speed. The gear 23 is driven by a bevel pinion 25, slid-

ably keyed on a main shaft 26, which is journaled in bearings 27, 28, and has affixed on it a large gear wheel 29, driven by a small gear 30, fixed on the shaft 31 of an electric motor 32. Said main shaft also has a small gear, 33, driving a larger gear 34 fixed on an idler shaft 35. On the latter shaft is fixed a pinion 36 driving a gear 37. The latter gear and a bevel-gear 38 are fixed 60 on a shaft 39. On said shaft 39 is slidably keyed a bevel pinion 40, having a peripherally grooved hub 41, engaged by a shifter lever 42, which is fulcrumed at 43 and by a rod 44 connected to a shifter 45, which 65 engages the hub of the bevel pinion 25, to move the latter out of mesh whenever the pinion 40 is moving into mesh with the gear 24. Said shifter 45 is provided with a hand lever 46 adapted to be placed alternately in 70 either one of three notches in a notched sector 47. When placed in the middle notch both pinions, 25 and 40 are idle and when the lever is in one of the other notches one or the other of the said pinions will be 75 thrown into mesh.

Fixed upon the rear side of the tub 7 is a mechanism frame 48, in whose lower end and in a bracket 49 on the tub is journaled a vertical shaft 50, having a bevel gear 85 51 driven by the bevel gear 38. On the upper end of the shaft 50 is fixed a collar 52 which supports the shaft. On said shaft is further fixed a bevel pinion 53, which rotates a bevel gear 54, rotating on a stud 55 90 fixed in the frame 48. The gear 54 has a crank pin 56 operating a pitman 57, the upper end of which is pivoted at 58 to a cross-head 59, which is guided on vertical bars 60 of the frame 48. 95

Fixed at 61 in the cross-head is the lower end of a standard 62, which is slidably guided in the upper end of frame 48. On said standard is fixed a head 63 having a rearward shoulder 64. The head may be 100 further secured to the cross-head by a brace 65. To said head 63 is pivoted at 66 the forked end of a horizontal arm 67, having branching arms 68, in which are secured the vertical rods 69 of two pounders 70. Said 105 pounders being fully described and claimed in my U. S. Patent, No. 1,313,497 of August 19, 1919 I need not herein repeat their structure. The forked end of the arm 67 is formed with a short downward finger 71 engaging in a notch 72 of a latch 73, which is 110 pivoted at 74 on the head 63 and is held

upward by a spring 75. For large machines such latch is made U-shaped so as to form one notched arm at each side of the head, and thereby engage a finger like 71 at each 5 side of the head. In Fig. 2 is shown that the shaft 26 may have a pulley 76, on which to place a belt from a pulley on a line shaft (not shown) where such is available, and in that case the electric motor 32 is dispensed 10 with.

Fixed on one side of the tub 7 is a resilient brake member 77 having a press button 78 projecting outward through an aperture, so that the operator may press it and therefore 15 cause the brake to act against the inner tub 12, especially against the rim 79 about its lower portion, and thus reduce speed of the rotation of the inner tub at the time it approaches the upper end of the screw 14.

20 In the operation of the machine a sufficient amount of cleansing fluid is put into the tub 7, the clothes to be cleansed are placed in the tub 12, the latter is lowered by either throwing the pinions 40 and 25 25 out of mesh and pressing downward on the edges of the tub by the hands, so that the screw 14, whose threads are for that purpose sufficiently slanting or steep, will rotate, or the tub may be lowered by resisting 30 its rotation during a proper rotation of the screw by the gears 40 and 24; or, the gearing and screw may stand still and the tub be given a rotary push or two by one hand 35 so it will descend on the screw, the latter being held still by the other hand placed on the handle 18. The gear 40 is then moved into mesh and the motor started. The 40 pounders will now move up and down and the inner tub will be rotated slowly by the gears 40—24 so as to move all the clothes in the tub along under the pounders. To insure such rotation of the inner tub, the cone 13 has a radical slot 80 with a lever 81 pivoted at 82 therein and having a spring 45 83 arranged to hold the upper end of it into a groove 84 in the screw (see Fig. 4).

When the pounding process is finished the motor is stopped, the fingers 71 released from the latch 73, and the pounders are 50 swung to the position shown in dotted line in Fig. 2, with the arm 67 resting upon the shoulder 64. The shifter lever 46 is then moved so as to disengage gear 40 and engage gear 25 with gear 23, and the lever 81 is 55 then touched by the operator so as to disengage it from the groove 84, as the motor is started. Said starting soon causes the rapid rotation of the screw to raise the lever 81 above the groove, where it then rides on 60 the top of the screw threads until the cone 13 enters the cone 15 and by frictional contact between the two cones enables the screw shaft 14 to rotate the tub 12 about five hundred revolutions per minute or any 65 other desired speed predetermined by the

gearing and the motor. During said fast rotation of tub 12 the cleansing fluid is forced outwardly by centrifugal force through the perforations of the tub and flows down below it into the outer tub 7. 70 The clothes are then removed, and replaced by the next lot of clothes to be washed. The operator now swings the top lever 18 to a horizontal position and uses it as a radial handle to prevent rotation of the shaft 14 75 while his other hand takes hold of the edge of the inner tub and by a slight turning movement separates the cones 13—15. The inner tub will now either rotate about the screw and get down in that way, or as already stated, the operator may place his hands upon opposite points of the top edge 80 thereof and press the tub down in a moment, causing the screw 14 and not the tub to rotate. When the tub is fully down the lever 85 81 will again engage in the groove 84 of the screw. The pounders are now replaced in the inner tub the gear 40 engaged with gear 24, the motor started and the whole operation just described is repeated. 90

From the foregoing description it will be seen that among other advantages of the machine it enables one to avoid the wear and tear to the clothes and other fabric caused by the usual rubbing process and 95 also by the wringing of the clothes through a wringing machine or other mechanism; and the pounders may readily be removed from the inner tub without detaching them from the mechanism operating them. Also 100 that by means of the two sleeves 9 and 10 it is impossible for the liquid to leak out around the shaft 14 although the latter has no stuffing box about it, and may thus rotate that much easier. 105

What I claim is:—

1. In a machine of the class described, a fluid-retaining main tub having a central sleeve projecting upward from its bottom, a perforated tub inside the main tub and having a central sleeve projecting upward from its bottom and arranged to rotate about the first mentioned or inner sleeve, a vertical shaft journaled in the inner sleeve and extending above both sleeves, means below the 110 bottom of the main tub for rotating the shaft at fast and at slow speed; the upper portion of said shaft constituting a screw and said outer sleeve having at its upper end a head threaded on said screw, means for locking the head to the lower part of the screw; said head on the sleeve having the shape of a cone, and the upper end of the screw having a fixed hollow cone adapted to receive the cone on the sleeve and engage it 115 frictionally.

2. In a machine of the class described, a fluid-retaining main tub having a central sleeve projecting upward from its bottom, a perforated tub inside the main tub and hav- 130

ing a central sleeve projecting upward from its bottom and arranged to rotate about the first mentioned or inner sleeve, a vertical shaft journaled in the inner sleeve and extending above both sleeves, means below the bottom of the main tub for rotating the shaft at fast or slow speed; the upper portion of said shaft constituting a screw, said outer sleeve having at its upper end a head

threaded on said screw, means for locking 10 the head to the lower part of the screw; said locking means consisting of a short groove in one side of the screw and a spring-pressed catch carried by the threaded head and arranged to engage in the groove. 15

In testimony whereof I affix my signature.

ANDREW B. MILLER.
